UNITED STATES PATENT OFFICE.

HENRY FRIED, OF BROOKLYN, NEW YORK.

DESIGN FOR A TOY.

49,301.

Specification for Design.

Patented July 4, 1916.

Application filed January 4, 1915. Serial No. 480 $\frac{1}{2}$. Term of patent 7 years.

To all whom it may concern:

Be it known that I, HENRY FRIED, a citizen of the United States, residing at Brooklyn, in the county of Kings and State of New York, have invented a new, original, and ornamental Design for Toys, of which the following is a specification, reference had to the accompanying drawing, forming part thereof.

Figure 1 is a side elevation of a toy illus-

trating my new design. Fig. 2 is a vertical front elevation thereof.

I claim:

The ornamental design for a toy as shown. Signed at New York, N. Y., Nov. 13, 1914.

HENRY FRIED.
